LABELING MACHINE

Richard Weber, Aurora, Ind., and James E. Grant,
Louisville, Ky., assignors to Joseph E. Seagram
& Sons, Inc., Shively, Ky., a corporation of Indiana

Application April 4, 1946, Serial No. 659,498

5 Claims. (Cl. 216—54)

1

This invention relates to an improvement in a labeling machine, and more particularly to a picker and gripper assembly for supporting and applying the labels to containers.

In labeling machines of the type wherein a container such as a whisky bottle, having a main body portion and a neck of much smaller size is moved past the rear face of a label-supporting picker, the attempted application of both a label to the body of the bottle and a label, such as a medallion or a neck ribbon to the neck of the bottle, has been unsatisfactory because of the difference in distance between the vertical plane of the body and neck portions and the picker. It has been found impractical to carry the neck by the gripper label from the picker to the bottle neck and still retain satisfactory control of the label. Because of such lack of control in a machine of this type, labels have been applied by hand.

In overcoming the aforesaid disadvantages of the prior art, it is an object of our invention to provide a novel picker and gripper assembly wherein control of the labels applied to any part of a bottle or like container having portions of different dimensions can be maintained.

A further object of our invention is to provide a novel picker and gripper assembly for a labeling machine of the type described wherein the labels to be applied to the several parts of a bottle or like container having portions of different sizes are all brought to a position closely adjacent the surfaces to which they are to be applied to enable control thereof during their application.

A further object of our invention is the provision of a novel picker and gripper assembly for a labeling machine of the type described whereby different labels can be applied to portions of a container of different sizes, the picker being so made that all the labels are acted upon by the gripper for substantially the same distance of travel, that distance being at a minimum whereby accurate and positive control of the labeling is insured.

Further objects and advantages of the invention will appear from the following description and claims taken in connection with the attached drawings wherein:

Fig. 1 is a perspective of a picker embodying my invention.

Fig. 2 is a side elevation of a gripper assembly employed in combination with the picker of Fig. 1.

Fig. 3 is a plan of a portion of the upper gripper of the assembly of Fig. 2.

2

Fig. 4 is a plan of a portion of the picker of Fig. 1 showing the roller operating means therefor.

Fig. 5 is a front elevation of the detail of Fig. 4.

Fig. 6 is a side elevation of the detail of Fig. 4.

Fig. 7 is a diagrammatic showing of the conventional picker and gripper assembly in position adjacent a bottle to be labeled.

Fig. 8 is a diagrammatic showing of the picker and gripper assembly of our invention adjacent a bottle to be labeled.

Fig. 9 is a perspective of a half of a modified picker embodying our invention.

Referring to Figs. 1, 4, 5 and 6, the picker element is formed of two spaced complementary sections 11 and 12. Each picker element includes a securing bracket 13 carrying the sections 11, 12 which provide adhesive receiving faces 14, the latter having a body-label receiving section 15 adapted to support a large label as of the type applied to the body of a bottle, and neck-label sections 16 adapted to support a small neck label or medallion to be applied to the neck of a bottle. The labels are applied to the sections 15, 16 straddling the middle space. Sections 16 are pivotally mounted on the bracket of the element by a shaft 17 secured to sections 16 to rotate therewith and mounted in a bore through the picker element. Shaft 17 extends through a spring bracket 18 (Figs. 4, 5 and 6) secured to the side of the picker element by screws 19, through a collar 21, and a lubricating washer 22, to a crank 23 to which it is fixed as by keying. A cam roller 24 is rotatably mounted on a pin 25 at the opposite end of crank 23 so when the roller is moved forward (clockwise) from the position shown in Figs. 1 and 6, the crank and shaft 17 are rotated to move the neck-label supporting sections 16 forwardly from the main face of the picker element. To hold sections 16 in their normal flush relation with the main section 15 of the picker element, a lug 25' is formed on crank 23 to engage one end of a tension spring 26, the other end of the spring being secured in a lug 27 on the end of a rearwardly extending projection 28 on lug 18. Normally sections 16 are in the position shown in Fig. 1.

In operation, the picker element having a neck label on sections 16 and a body label on section 15 straddling the middle space is moved to a position adjacent the bottle to be labeled, the picker normally rotating in well known manner about a pivot just above brackets 13 in the direction of the arrow shown in Figure 1. Two fixed lugs or cams 30 are provided, one on each side, in the

paths of rollers 24 so that as the picker element approaches labeling position, rollers 24 are stopped. Continued forward movement of the picker causes cranks 23 and shaft 17 to rotate, and thus pivot neck label sections 16 forwardly from the main face 14 of the picker and positions the two neck sections closely adjacent the bottle to be labeled.

This action can best be understood from the diagrammatic showing of Figs. 7 and 8 wherein a bottle having a main body portion B and a neck N of smaller diameter is shown in plan. The conventional picker with elements 11 and 12 and a label L supported thereon is shown in labeling position adjacent the bottle in Fig. 7, the conventional gripper being shown at G. While the length of travel of the label to section B of the bottle is relatively short, the distance to neck N, indicated at X, is so long that the gripper cannot maintain satisfactory control 10 of the neck label and the label cannot be applied satisfactorily with such a picker.

With the picker of Fig. 1, the operation is as shown in Fig. 8, the picker sections 11 and 12, carrying the label L for body B of the bottle, being disposed in their normal position while sections 16, bearing the neck label L', are moved forwardly toward the bottle and past elements 11 and 12 to a position closely adjacent neck N of the bottle. Thus gripper element G' need only maintain control of the label L' through the distance Y, a distance comparable to the normal distance between label L and the body B of the bottle. With this reduction in distance effected by the picker disclosed herein, satisfactory control over the neck labels has been secured and it is thus possible to apply them simultaneously with the body labels.

The gripper assembly preferably employed with the picker of Fig. 1 is shown in Figs. 2 and 3 and includes a bracket 31 for conventional mounting on a support so that the assembly can be rotated in a manner to pass the grippers between the elements of the picker, a lower gripper 32, and an upper gripper 33. The lower gripper 32 is preferably formed integral with bracket 31 and rises by a goose-neck formation to a lug 34 having a frame 35 channeled and pivoted thereon at 36, the frame mounting a relatively soft rubber face 37. A stop 38 is provided to limit the clockwise motion of the gripper and an adjustable screw 39 to limit the counterclockwise motion thereof, the gripper thus being rotatably adjustable about pivot 36 to the best angle for controlling the main label.

Plates 41 are secured to opposite sides of the goose neck as by screws 42 to form a supporting channel for the upper gripper assembly, the latter having its lower end 43 pivoted between the plates at 44. The upper gripper assembly 60 rises from end portion 43 on a curve to a head 45 having the upper gripper 46 channeled thereon and pivoted at 47. Gripper 46 mounts a rubber face 48, having an angularly disposed U-shaped open end 49 for better control of the neck labels in applying them to the rounded necks of the bottles. The upper gripper is adjustable on head 45 by screws 51 and 52, the head being pivotally adjustable on the lower gripper by a screw 53 acting against the compression 70 of a spring 54.

In operation, the lower gripper operates in a manner well known to the art in passing between the two gripper elements 11 and 12 as shown in Fig. 7 and carrying the label L onto the main

body portion B of the bottle and off of the supporting picker. Simultaneously the upper gripper G' which is in advance of the lower gripper removes the neck label L' from the hinged picker elements 16 and carries it against the bottle neck N. Control of the label is aided by the shape of the face formed on the rubber face of the upper gripper, the application of the label to the bottle neck being facilitated by the U-shaped recess in the face of the gripper and the angular inclination thereof as shown in Fig. 2 which conform generally to the shape and angle of the bottle neck surface.

In Fig. 9, we have shown a modification of the picker element of Fig. 1 wherein the main face of the element 61 is recessed to receive a neck label supporting section 62, the latter being supported in the recess by an arm 63 pivoted on a hinge pin 64, the outer end of the arm carrying a pin 65 mounting a cam roller 66. Hinge pin 64 is supported in a lug 67 secured to the side of the picker element and hollowed at 68 to receive a coil spring 69 having its ends secured in recesses in lug 67 and the adjacent section of arm 63. Thus as the picker element is moved to labeling position, as already described in connection with the picker of Fig. 1, cam roller 66 is actuated by a fixed cam (not shown) to pivot arm 63 on pin 64 and move the neck-label supporting section 62 forwardly of the main face of the picker element and position the neck label supported thereon immediately adjacent the neck N of the bottle in the position shown in Fig. 8. On return movement 30 of the picker element, spring 69 returns section 62 to the position shown in Fig. 9. In all other respects, the picker element of Fig. 9 is similar to that of Fig. 1, it being understood that a complementary picker element is employed therewith as with the picker of Fig. 1.

From the foregoing, it is believed evident that we have provided a picker and gripper assembly capable of satisfactorily applying the neck and main labels to a bottle or like container simultaneously, the picker being essentially simple in mechanism and operation and requiring no more attention as regards maintenance than the conventional picker.

Having described our invention, we claim:

1. An assembly for use in a labeling machine for applying labels to a bottle or similar container of the type having a main body portion and a neck portion of smaller size, comprising: a picker including two spaced substantially flat-faced elements, each element having a first label-receiving section adapted to cooperate with a first label-receiving section on the other element to receive and support the bottle side of a label for application to the main body portion of the bottle, and a second label-receiving section adapted to cooperate with a second label-receiving section on the other element to receive and support the bottle side of a label for application to the neck portion of the bottle, means on said elements to mount said second sections in a common plane with said first sections and in a manner to be displaced forwardly of the first sections; means to move the picker from a label-receiving position to a label-applying position; means to cause the second sections to be displaced forwardly toward and adjacent the neck of the bottle when the picker is moved to a position to apply the label to the main body portion of the bottle.

2. In a labeling machine for applying labels to a bottle having a main body portion and a

neck portion of smaller size, said machine having a slotted picker element for positioning adhesive-coated labels adjacent the bottle, and a gripper adapted to pass through the slot of the picker element for simultaneously applying the labels to the bottle, the improvement wherein: the picker element comprises a pair of spaced plates for receiving the adhesive-coated body label straddled over the space, in position to be engaged by the gripper in its movement between the plates, and a second pair of spaced plates pivotally supported for receiving the adhesive-coated neck label straddled over the space in position to be engaged by the gripper in its movement between the latter plates; and means adjacent the label-applying position for advancing said second pair of plates relative to the first mentioned pair of plates to bring the label carried thereby closely adjacent the bottle neck whereby the gripper substantially simultaneously attaches the body and neck labels to the bottle.

3. A machine for applying labels to a bottle or similar container having a main body portion and a neck portion of smaller size comprising: a label picker having a first section presenting a face to receive and support a body label straddling a middle slot therein, and a second pair of sections pivotally supported in spaced relation on the first section and adapted to receive and support a neck

label straddling the space therebetween; and means at the label-applying position to pivot said second sections relative to the first section to position the neck label thereon in advance of the body label and substantially parallel therewith.

4. A machine as specified in claim 3 wherein said means comprises a stop at the label-applying position to pivot the second sections while the first section advances.

5. The assembly of claim 3 wherein means is provided to return the label-receiving faces of said sections to substantial alignment when said picker is not positioned closely adjacent the bottle.
